UNITED STATES PATENT OFFICE.

PETER S. LAWTON, OF NEW ORLEANS, LOUISIANA.

RIVERSIDE SILTLESS BASIN.

1,275,273.

Specification of Letters Patent. Patented Aug. 13, 1918.

Application filed May 1, 1917. Serial No. 165,683.

To all whom it may concern:

Be it known that I, PETER S. LAWTON, a citizen of the United States, residing at New Orleans, in the county of Orleans and State 5 of Louisiana, have invented certain new and useful Improvements in Riverside Siltless Basins, of which the following is a specification.

This invention relates to new and useful 10 improvements in basins for repair docks and building ways along silt-bearing rivers.

The primary object of the invention is the provision of a docking place in slack and siltless water for vessels arranged in connection with repair shops whereby a vessel 15 is readily docked at the shop regardless of the strong current in the river, the silt deposits therein, or the strong winds, waves, etc., which hinder the handling of such 20 vessels.

A further object of the invention is the provision of a deep still-water basin having a guarded approach from a silt-bearing river with strong current, while a shallow basin 25 of constant depth is connected with said still-water basin being provided with launching ways readily accessible from any point upon the land.

With these general objects in view, the de- 30 vice broadly consists in the combination and arrangement of parts hereinafter fully described as well as claimed, the same being illustrated in the accompanying drawing in which like-reference characters designate 35 corresponding parts throughout the same.

Referring more in detail to the view set forth in the drawing it will be noted that the numeral 5 represents the land or river bank adjacent the water as at 6, which represents 40 such a river as the lower Mississippi, having a strong current with immense deposits of silt in the river which is being constantly carried down by the current toward the Gulf of Mexico. The usual levee or wall 7 being 45 provided at the side of the river, wharves 8 and 9 are arranged in the usual manner spaced apart adjacent the levee 7, the wharf 8 being positioned up-stream from the wharf 9, boats 10 being shown positioned in 50 deep water of the river 6 adjacent the lower wharf 9.

A deep-water basin 11 is arranged inwardly of the levee 7, having a guarded entrance 12 from the river and being provided

with a marginal wharf 13 in the form of a 55 wall surrounding the basin and being of the same height and connected with the wharves 8 and 9.

The guarded entrance 12 is formed by a down-stream projection 14 of the wharf 8 60 which projection extends outwardly into the river and is formed by driving sheet piling 15 into the river bed, said sheet piling 15 extending at an acute angle from the levee 7 to the outermost point of the wharf 8. By this construction it will be seen that silt laden water in passing down stream will strike the piling 15 and be deflected away from the entrance 20 and the wharf 9. A like projection 16 extends within the basin 11. This projection is also formed by driving sheet piling 15^a into the basin bed. Both projections 14 and 16 extend to a point beyond the end of the wharf 9. It will thus be seen 65 that the entrance from the river 6 to the basin 11 is through a passage extending upstream and diagonally inward, then downstream and again inward until the main basin is reached. By this arrangement sediment is prevented from entering the basin 70 11 due to the fact that the water is deflected away from the guarded entrance by the sheet piling 15.

And further, sediment can not be blown 75 into the basin 11 as any wind tending to blow water into the basin from the river would also strike the sheet piling 15^a, with the resultant effect upon the water that the water tending to come from the river would be checked by the water being blown from 80 within the basin, or, in other words, any wind blowing up-stream would strike the sheet piling 15 and 15^a and would become pocketed at 12, which pocketing effect would be the same as a cushion, thereby preventing 85 the wind from having any effect upon the water.

It will be seen that by this construction a boat, as shown at 10, would pass within the guarded passage 12 and back into the basin 100 11 regardless of the conditions in the river, and at no time will the strong current, due to high water affect the docking. Any silt deposited in the guarded entrance 12, due to slow settling of the sediment in the water 105 adjacent the river, and water which may enter the basin 11 when the river rises, can be easily forced through the opening 20 into

the river 6 by means of water jets, agitators or small suction dredges located within the pocket 12.

Within the basin 11 any number of floating docks such as 21, 22 or 23 may be provided with excavations beneath the same so that they may sink to a proper depth in accommodating large vessels. It is absolutely impossible to accommodate floating docks of this character within a silt bearing river as the excavations into which they sink when submerged so rapidly fill up with silt that the expense of dredging is prohibitive; and moreover, several serious accidents have resulted from the turning over of these floating docks, due to the action of the current, when rising with a vessel.

It will also be noted that I have provided projecting docks 24 and 25 to which several vessels can moor and be adjacent to overhead cranes and land machinery, which could not be used upon the docks located near the levee without endangering the levee. Tracks 26 are provided whereby material and suitable apparatus may be moved about the yards with safety and facility. At 27 I have provided a lock canal having double gates 28. This canal forms a passage way for boats between the basin 11 and the fixed level basin 29. The level of this basin is maintained by suitable pumps or through the medium of a spill-way 30. Adjacent to the basin 29 I have provided ways 31 upon which vessels 32 may be constructed and readily launched.

It will be noted that by this arrangement, the canal 27 and gates 28 are so remotely removed from the river that the danger to the levees is also lessened, as it is quite difficult to maintain tight gates at a levee owing to the constant settling of the surrounding ground, and further the sediment seriously affects the operation of the gates, whereas

the gates to my lock are so far from the river as to be in clear water where they can be operated without difficulty.

What I claim as new is:

1. An entrance for a basin located adjacent to a silt bearing river comprising two diverging wharves, said wharves diverging in the direction of the flow of the river, a third wharf projecting upstream having its end between said diverging wharves and in spaced relation thereto.

2. An entrance to a basin comprising a wharf projecting downstream and slightly outward into a silt bearing river, a wharf extending upstream and having its end overlapping said first mentioned wharf, and protected from the river current by said first mentioned wharf, a third wharf diverging from said first wharf and overlapping said second wharf, and in spaced relation thereto.

3. A basin entrance comprising two diverging wharves and a third wharf projecting upstream between the said wharves and spaced from said wharves a sufficient distance to allow entrance by vessel between the wharves.

4. A basin entrance comprising two diverging wharves and a third wharf projecting upstream between the first mentioned wharves so that the water enters the basin in a V shaped course.

5. A basin entrance comprising two diverging wharves adapted to counteract the blowing in of silt laden water from the outer river through the pocketing of the wind and driven water from both the river and basin within the pocket formed by the diverging wharves, a third wharf projecting upstream and spaced away from but between said diverging wharves.

In testimony whereof I affix my signature.

PETER S. LAWTON.
